Primary Examiner — Messina L Smith*(74) Attorney, Agent, or Firm* — Amin, Turocy & Watson,
LLP(57) **CLAIM**The ornamental design for an on-vehicle speaker, as shown
and described.**DESCRIPTION**FIG. 1 is a right, front, and bottom perspective view of an
on-vehicle speaker showing my new design;

FIG. 2 is a right, rear, and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the drawings are for the purpose of
illustrating portions of the on-vehicle speaker that form no
part of the claimed design.**1 Claim, 8 Drawing Sheets**| (56)	References Cited
